MACHINE FOR OPERATING ON FOOTWEAR

Filed June 13, 1925

UNITED STATES PATENT OFFICE.

RENÉ E. DUPLESSIS, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON FOOTWEAR.

Application filed June 13, 1925. Serial No. 36,922.

This invention relates to machines for use in the manufacture of boots and shoes and is herein illustrated as embodied in a machine for use in preparing the heel-seats of shoes 5 for the reception of wood or other heels to be attached thereto.

In the preparation of the rear portion of a shoe bottom for the reception of a heel such as a wood heel, that is, one having a scoop-shaped heel-seat surrounded by a peripheral rim, preferably two operations are performed, the first being the heel-seat fitting operation which consists in the removal of material from the margin of the rear end of 10 the sole, and the second being the heel-seat forming operation which consists in molding the remaining portion of the heel end of the sole and the other adjacent materials into a convex shape corresponding substantially to 15 the concavity in the seat of the heel.

Objects of the present invention are to provide a machine for performing this heel-seat forming operation with greater accuracy, increased speed, economy and convenience, and 20 hence to facilitate the manufacture of wood heeled shoes.

For the attainment of these objects, the invention is herein exemplified as embodied in a novel machine of the type having a die and 25 a last support relatively moved to effect pressure of the die upon the heel-seat of a shoe upon the last. In order properly to position the die and heel-seat of a shoe relatively to each other for the forming operation, the invention provides for convenient relative 30 movement of the die and heel-seat so that the die and heel-seat may be readily centralized with respect to each other, that is, so that the center of the heel-seat may be brought into 35 position opposite the center of the face of the die. In another aspect, the invention also makes provision for relative movement of the die and heel-seat so that the plane of the heel-seat and the plane of the die may be relatively adjusted to establish parallelism between them. As a further feature, to insure 40 against accidental relative displacement of the shoe and support after they have been properly positioned with relation to each 45 other, there is provision for relative movement of the die and shoe support perpendicular to the heel-seat to bring them in contact with sufficient pressure to prevent accidental 50

displacement, which pressure may be released if the relative positions of the die and shoe 55 are found unsatisfactory and further adjustments made before re-applying the pressure.

Accordingly, the illustrated machine comprises a fixed die having its face downwardly directed and nearly horizontal, and a shoe support movable longitudinally and transversely of the die in a plane substantially parallel to the face of the die to enable the heel-seat to be centralized under the die. The illustrated work support is adjustable about 60 axes extending transversely and longitudinally of the heel-seat to bring the heel-seat into parallelism to the face of the die. Manually operable means is provided for raising the work support to force the heel-seat 65 against the die with sufficient preliminary pressure to prevent its displacement until the molding pressure is applied and for lowering the work support if the heel-seat is improperly positioned with respect to the die. 70

It is desirable that the space about the shoe and die be opened and unencumbered with mechanism and that the relative position of the die and shoe may be readily observable 75 by the operator while standing in his usual position in front of the machine.

Hence, in the illustrated construction, the die is supported with its periphery in full view and the longitudinal axes of the work support and die support are tilted back at an 80 angle of approximately ten degrees to enable the operator more conveniently to inspect the shoe and determine the proper relative position of the shoe and die. 85

It is important that, after the shoe and die have been properly positioned relatively to each other, the heel-seat be subjected to heavy pressure. Accordingly, the illustrated machine is organized to effect relative movement of the die and support by power to apply 90 heavy molding pressure to form the heel-seat of the shoe in the desired manner. As herein illustrated, the power mechanism comprises a toggle supported by a powerful spring, the joint of the toggle having a lost motion connection to an eccentric which is operated by power to straighten the toggle. Conveniently, a treadle is arranged first to raise the work support slightly to press the work 95 against the die and, upon further movement, to trip a half revolution clutch to cause a 100

semirotation of the eccentric and place the work under pressure.

While the work is under pressure it is customary, in the case of some kinds of shoes such, for example, as patent leather shoes, to pound the counter portion of the shoe with a hand hammer, the purpose being to bring the upper and counter about the rear end of the last into better condition to receive the heel.

In order to enable this operation to be more conveniently performed, the illustrated shoe support and the die are so arranged that the longitudinal axis of the shoe while under pressure extends rearwardly of the machine and toward the operator's left at an angle of substantially forty-five degrees, this position having been found most convenient for access of a right handed operator to the shoe with a hand hammer. Of course, the parts may be so constructed that the shoe will be positioned ninety degrees toward the right from the position described in case it is desired to accommodate a left hand operator.

These and other features of the invention will appear more fully from the following description when read in connection with the accompanying drawings and will be pointed out in the appended claims.

In the drawings:

Fig. 1 is a side elevation of the machine, the front of the machine being at the right, and

Fig. 2 is a perspective view, partly exploded, of the shoe support mechanism shown in Fig. 1.

Referring to Fig. 1, the numeral 2 indicates the frame of the machine, secured to the upper part of which is a backwardly tilted framework comprising a head 4 rigidly supported by heavy rods 6. Secured to the head 4 is a die support 10. Fixed on the lower end of the die support is a die 12 having a stem 14 extending up into the die support and provided at one side with a slot in the bottom of which is a recess. Mounted in the die support is a spring pin 16 which enters the slot in the stem 14 to prevent turning of the die and, when the die engages the support, enters the recess to prevent the die from dropping out. By pulling outwardly on the pin 16 the die may be released, removed, and another die substituted for it.

A last pin 17 is mounted on a substantially semi-cylindrical rocking member 18 which is seated in a block 19 and is held in place by plates 20 secured to the block 19 and having inwardly projecting pins 21 which engage curved slots 23 in the ends of the member 18. The spacing of the plates 20 and the length of the pins 21 is such, relatively to the length of the member 18, that there is a small amount of relative lengthwise movement between the member 18 and the block 19. The block 19 is dovetailed to

a member 24 for rectilinear sliding movement laterally of the shoe and a spring pin 25 is seated in the member 24 with its upper end in engagement with a groove 26 in the bottom surface of the block 19 to hold the block frictionally in place and prevent unintentional movement thereof relatively to the member 24. A pin 27 projecting from the spring pin 25 holds it in place and may be used to depress the pin to permit removal of the block 19. The lower portion of the member 24 is reduced in width to be embraced by the bifurcated upper end of a large screw 28. In the bottom of the slot forming the bifurcations is seated a block 29 having teeth on its upper face to be engaged by teeth formed on the lower end of the member 24. The member 24 has curved surfaces which engage corresponding curved surfaces on the upper ends of the bifurcations of the screw 28, and the toothed lower end of the member 24 is also similarly curved, the center of these curvatures lying approximately in the surface of the heel-seat of a shoe on the support. A screw 30 passes freely through one of the bifurcations of the screw 28, through a slot 31 in the member 24, and is threaded into the opposite bifurcation, so that tightening of the screw acts to clamp the member 24 between the bifurcations. The slot 31 is wide enough so that when the screw 30 is loosened the member 24 may be lifted sufficiently to release the teeth in its lower surface from the teeth on the block 29, thus permitting the upper parts of the support and the shoe to be adjusted in the longitudinal median plane of the shoe about a center lying substantially in the plane of the heel-seat so as to distribute properly the pressure of the die upon the front and rear portions of the heel-seat. The screw 28 is mounted to slide freely up and down in a post 32 and is prevented from turning in the post by a block 35 held to the post by a pin 37 and engaging a groove 39 formed therein. A large nut 34 is threaded on the screw 28 and rests on the top of the post 32. It will now be clear that the vertical position of the last pin may be quickly adjusted by turning the nut 34; that the pressure of the die upon the front and rear portions of heel-seat may be varied or equalized by tipping the last pin and shoe in the longitudinal median plane of the shoe after loosening the screw 30, that the position of the heel-seat of the shoe with respect to the die may be varied in a plane parallel to the acting face of the die by sliding the block 19 transversely of the member 24 or by sliding the member 18 relatively to the block 19; and that the pressure of the die upon the two sides of the heel-seat may be equalized by rocking the member 18 on which the cone of the last rests and which carries the last pin 17.

The post 32 is pivoted at 36 to the upper

end of a shaft 38 which is mounted for sliding movement in the frame 2 with its longitudinal axis in alignment with the longitudinal axis of the die support 10, these axes being 5 tilted rearwardly at approximately ten degrees to the vertical. The links 40, 42 of a toggle are connected together at 44, the other end of the link 40 being pivoted at 46 to the shaft 38 and the other end of the link 42 10 being pivoted at 48 to a sleeve member 50 which is arranged to slide in a guideway formed in the frame of the machine and in alignment with the shaft 38. Inside of the sleeve member 50 is a long stiff spring 52 arranged to be compressed by downward movement of the sleeve member 50. An adjustable rod 54 is connected at its upper end to the upper pivot 46 of the toggle and at its lower end is pivoted at 56 to a lever 58 ful- 15 crumed at 60 on the frame. The rear end of the lever 58 is forked to embrace a rod 62 which, at its lower end, is connected at 64 to a treadle 66 which is raised by a treadle spring 68. On the rod 62 is a sliding collar 20 70 which lies upon the forked rear end of the lever 58 and between the collar and an adjusting nut 72 on the rod 62 is a spring 74. At its upper end the rod 62 has a lost motion connection at 76 with a clutch stop arm 30 78. The toggle 40, 42 is straightened by power operated mechanism comprising an eccentric strap 80 which has at its forward end a slot 82 to receive the pin 44 forming the joint of the toggle. The eccentric strap 80 35 embraces an eccentric 84 on a shaft 86. By means of a suitable one-half revolution clutch mechanism the eccentric may be connected to a continuously rotating gear 88 with which a pinion 90 on a shaft 92 meshes. 40 On the shaft 92 is a gear 94 which is in mesh with a pinion 96 of an electric motor 98.

The clutch stop arm 78 is pivoted at 100 and is held in operative position by a spring 79. On the same pivot 100 is a lever 102 one arm 45 of which is operated by the lost motion connection at 76 with the rod 62. The other arm of the lever 102 engages a latch 104 pivoted on the stop arm 78 and held against a stop pin 101 by a spring 103. One end of the latch 50 has a hook to engage the end of the lever 102 and the other end carries a roll 105 which is lifted by projections 106 arranged to rotate with the eccentric 84 and caused to release the latch 102. When the treadle is depressed 55 the lever member 102 is swung in a clockwise direction and, because of the engagement of the latch 104 therewith, moves the stop arm 78 in the same direction, causing an adjustable block 107 on the stop arm to release a 60 clutch projection 108 so that the machine will start. Early in the rotation of the eccentric, one of the cams 106 engages the roll 105 on the latch 104 and moves the latch to release the lever 102 which allows the stop arm 65 78 to drop back in position to engage the stop

projection 110 after the eccentric 84 has completed a half revolution. This mechanism ensures that the machine will stop after a half revolution even if the operator holds the treadle depressed. A spring-pressed pawl 70 112 carried by the stop arm 78 is arranged to engage a radial face on one of the cam projections 106 to prevent backward motion of the eccentric when the machine comes to rest, the weight of the eccentric at that time 75 being rearwardly off center and tending to turn backward.

The machine stops after one half revolution of the eccentric 84 on the shaft 86 with the toggle substantially straight and the 80 spring 52 strongly compressed. When started again by another depression of the treadle to bring the machine back to open or normal position, the spring 52 reacts strongly 85 through the toggle and eccentric and tends to turn the eccentric faster than the gear 88 is turned by the motor 98. This results in strain, wear, and possible breakage of the clutch by which the eccentric and driven gear 88 are connected. To prevent the eccentric 90 from thus running ahead of its operating mechanism, the following means is provided: A brake band 120 has one end fixed at 122 to an arm 124 pivoted at 100 and the other end of the band is connected at 126 to a rod 128 arranged to slide through a pin 130. The lower portion of the rod is enlarged to limit upward movement of the rod through the pin. On the rod 128 between the pin 130 and adjusting nuts 132 is a spring 134 the initial 95 tension of which can be varied by adjusting the nuts 132, since upward movement of the rod relatively to the pin 130 is limited. The pin 128 is mounted between ears on one arm 136 of an angle lever which is pivoted at 138 100 on the same arm 124 to which the opposite end of the band is fastened. The other arm 140 of the angle lever carries a roll 142 which is engaged by a cam 144 carried by the eccentric. When the machine is restarted with 105 the work under pressure, the cam 144 is in position immediately to lift the roll 142 and cause tension to be applied to the band 120 through the spring 134. Thus, movement of the eccentric is retarded until the tension of 110 the spring 52 has been relieved. When the band is tightened a curved surface 146 on the arm 124 is brought into engagement with the surface of the band drum between the ends of the band and assists in the braking 115 action of the band.

As shown in Fig. 1, the framework carrying the head 4 is tilted backwardly, at an angle of approximately ten degrees to the vertical, with respect to the operator's position in front of the machine, that is, at the right of Fig. 1. This construction renders it much easier for the operator to see whether the heel-seat of a shoe on the support is properly located with respect to the die when 130

they are brought into close relation or pressed together by the manually effected upward movement of the work support.

It will also be noted that the die and work support are so arranged that the longitudinal axis of a shoe on the support will extend rearwardly and toward the left from the operator's position in front of the machine, that is, the longitudinal axis of the shoe is located at an angle of substantially forty-five degrees to the fore-and-aft plane of the machine. This position of the shoe renders it easy and convenient for the operator to pound the counter portion of the shoe with a hand hammer held in his right hand. Of course, in the case of a left-handed operator the shoe will be positioned with its longitudinal axis extending rearwardly and toward the right at an angle of forty-five degrees to the fore-and-aft plane of the machine.

In the operation of the machine, the last of a shoe such as a turn or McKay shoe, to which a wood heel is to be attached, is placed upon the last pin 17, the heel-seat of the shoe having been previously fitted by the removal of the peripheral portion of the heel end of the sole. The operator, grasping the shoe, tips the support about the axis 36 to locate the heel-seat of the shoe longitudinally under the die and moves the block 19 of the shoe support laterally, if necessary, to locate the heel-seat laterally with respect to the die. If the space between the heel-seat and the die is substantial, he will operate the nut 34 to raise the work support and bring the heel-seat in close relation to or against the die 12. Parallelism between the die and the heel-seat is effected in the manner described by adjustment of the work support in the longitudinal median plane of the shoe about an axis lying approximately in the plane of the heel-seat, and by rocking of the member 18 which carries the last pin with respect to the block 19. The heel-seat having been properly located with respect to the die, the operator depresses the treadle 66, thus pulling down on the rod 62 which acts, through the spring 74, lever 58 and rod 54, to raise the shaft 38 carrying the work support, thus pressing the heel-seat of the shoe yieldingly against the die and preventing any accidental displacement of the shoe. The upward movement of the shaft 38 and consequent slight straightening of the toggle 40, 42 is permitted by the short slot 82 in the forward end of the eccentric strap 80. The nut 34 will preferably be so adjusted that the movement of the work support effected by the treadle will always be slight. In fact, if desired, the nut 34 may be used to apply sufficient pressure of the heel-seat against the die to maintain the shoe in adjusted position, in which event little, if any, straightening of the toggle will occur when the treadle is depressed. Further depression of the

treadle, after the shoe is raised against the die, will cause the spring 74 to be compressed and the lost motion connection 76 to be taken up, the final movement of the treadle acting to throw outwardly the stop arm 78 of the clutch and cause power operation of the machine to commence. A half revolution will then be imparted to the eccentric which, through the eccentric strap 80, acts to straighten the toggle and apply powerful pressure to force the heel-seat against the die, this pressure being rendered yielding by the spring 52. The strength and the amount of compression of the spring 52 determines the amount of pressure which will be applied to the shoe by the straightening of the toggle. It will be noted that the spring 52 is relatively long so that a slight difference in the amount of compression of the spring does not greatly affect the amount of pressure applied to the shoe.

The machine is arranged to stop with the work under pressure and conveniently the machine is of the duplex type, a mechanism similar to that described being arranged alongside, supported on the same framework and operated by a separate clutch from the common gear 88.

Having thus described my invention, what I claim as new and desire to secure by Letters Patent of the United States is:

1. In a heel-seat forming machine, the combination of a fixed heel-seat die formed to shape the heel-seat of a shoe on a last for the reception of a wood heel, a last support adjustable laterally and longitudinally of the heel-seat of a shoe on a last carried by said support to center the heel-seat of the shoe in respect to the die, means under manual control for effecting a preliminary movement of the last support toward the die to facilitate the centering of the heel-seat of the shoe, and power-operated means for relatively operating the die and support to impress the die on the heel-seat of the shoe.

2. In a heel-seat forming machine, the combination of a fixed heel-seat die formed to shape the heel-seat of a shoe on a last for the reception of a wood heel, a last support adjustable laterally and longitudinally of the heel-seat of a shoe on a last carried by said support to center the heel-seat of the shoe in respect to the die, means under manual control for effecting a preliminary movement of the last support toward the die to facilitate the centering of the heel-seat of the shoe, and power-operated means for continuing the manually controlled movement of the support to impress the die on the heel-seat of the shoe.

3. In a machine for forming the heel-seats of shoes for the reception of wood heels, the combination of a heel-seat forming die, a shoe support movable toward the die, said die and support being constructed and arranged to have sufficient relative positioning movement

in any direction in a plane substantially parallel to the plane of the heel-seat to enable the die and heel-seat to be positioned properly relatively to each other, and power operated means for moving the support heightwise of the shoe relatively to the die to form the heel-seat.

4. In a heel-seat forming machine, the combination of a heel-seat forming die, a shoe support arranged to have sufficient positioning movement in any direction with respect to the die in a plane substantially parallel to the acting face of the die to enable the die and heel-seat to be positioned properly relatively to each other, means for relatively moving the die and the support heightwise of the shoe to bring the shoe and die into contact and to apply sufficient pressure to hold the die and shoe in proper relative position, and means for further relatively operating the support and die to force the die into the heel-seat material.

5. In a heel-seat forming machine, the combination of a heel-seat forming die, a shoe support arranged to have sufficient positioning movement in any direction with respect to the die in a plane substantially parallel to the acting face of the die to enable the die and heel-seat to be positioned properly relatively to each other, means for effecting a preliminary relative movement of the die and support into operative relation and for holding the shoe against accidental displacement relatively to the die, and power means for effecting further relative movement of the shoe support and die to effect molding of the heel-seat by the die.

6. In a machine for forming the heel-seats of shoes for the reception of wood heels, the combination of a fixed heel-seat die having a shape similar to the heel-seat of a wood heel, a shoe support arranged for horizontal movement in two directions at right angles to each other and for tipping movement laterally of the shoe, manual means for moving the shoe support to enable the operator to adjust the support in parallelism with respect to the die and to hold the shoe in operative relation against the die, and power operated means for effecting further relative movement of the shoe support and die to effect molding of the heel-seat by the die.

7. In a machine for forming the heel-seats of boots and shoes, the combination of a heel-seat forming die having a shape similar to that of the heel-seat of a wood heel, a last support beneath the die and arranged for movement longitudinally of the die and for lateral sliding movement to permit a shoe and last on the support to be manipulated relatively to the die for locating the heel-seat widthwise of the shoe properly relatively to the die, a treadle for raising the support to press the shoe against the die after the shoe has been properly located with respect there-

to, and means rendered operative by further movement of the treadle for applying heavy pressure to the heel-seat of the shoe.

8. In a machine for forming the heel-seats of shoes for the reception of wood heels, the combination of a fixed heel-seat die having the shape of the heel-seat portion of a wood heel, a shoe support movable toward the die, manual means for lifting the shoe support to hold the shoe in operative relation to the die, and power operated means arranged to be brought into action by continued movement of said manual means for applying powerful pressure to the shoe support to cause the die to impart the shape of the die to the heel-seat of the shoe.

9. In a heel-seat forming machine the combination of a heel-seat forming die, a shoe support arranged for positioning movement laterally with respect to the die, a heavy spring beneath the support, a toggle between the spring and the support, means for relatively moving the die and the support heightwise of the shoe to bring the support and die into contact and to apply sufficient pressure to hold the die and shoe in proper relative position, and power means for operating the toggle to lift the support and to force the die upon the heel-seat material with pressure determined by said spring.

10. In a machine for forming the heel-seats of shoes for the reception of wood heels, the combination of a fixed heel-seat die having a pressing face similar in shape to the heel-seat of a wood heel, a shoe support, a treadle for moving the shoe support toward the die so that the die and heel-seat may be placed in proper relative position and so held, power operated means including a toggle and a heavy spring for effecting further movement of the shoe support toward the die to effect molding of the heel-seat by the die, and means controlled by said treadle for initiating the operation of the power operated means.

11. In a machine for forming the heel-seats of shoes for the reception of wood heels, the combination of a fixed heel-seat die having a pressing face similar in shape to the heel-seat of a wood heel, a shoe support, a toggle for raising the shoe support, power operated means having a lost motion connection to said toggle, a treadle for moving the shoe support as permitted by the lost motion connection so that the die and the heel-seat of a shoe on the support may be brought into proper relative position and so held, said power operated means being operative to cause further movement of the shoe support toward the die to effect molding of the heel-seat by the die, and means controlled by said treadle for initiating the operation of the power operated means.

12. In a machine for forming the heel-seats of shoes for the reception of wood heels, the combination of a heel-seat die having a press-

- ing face similar in shape to the heel-seat of a wood heel, a shoe support movable toward the die, said die and support being constructed and arranged for sufficient relative positioning movement in all directions in a plane substantially parallel to the plane of the heel-seat to enable the die and heel-seat to be properly centralized with respect to each other, means for effecting a preliminary relative movement of the die and support to bring the shoe and die into operative relation and to hold the shoe against accidental displacement relatively to the die, and power operated means for moving the support relatively to the die to form the heel-seat.
13. In a machine for forming the heel-seats of boots and shoes, the combination of a heel-seat forming die for shaping the heel-seat portion only of a shoe for the reception of a wood heel, a last support arranged for swinging movement longitudinally of a shoe to permit a shoe and last on the support to be located longitudinally relatively to the die, a last pin on said support movable laterally of said swinging movement to permit lateral positioning of the shoe relatively to the die, a treadle for raising the support to press the shoe against the die after the shoe has been properly located with respect thereto, and means operated by further movement of the treadle for applying heavy pressure to the heel-seat of the shoe.
14. In a machine for forming the heel-seats of boots and shoes, the combination of a fixed heel-seat die for shaping the heel-seat portion only of a shoe for the reception of a wood heel, a shoe support movable toward the die, a toggle for moving the shoe support, power operated means for actuating the toggle, there being provision for movement of the shoe support ahead of said power means, a treadle for lifting the shoe support to hold the shoe in operative relation to the die, said power operated means being arranged to be brought into action by continued movement of said treadle for operating the toggle to apply powerful pressure to the shoe support, and a yielding connection between the treadle and the shoe support.
15. In a heel-seat forming machine, the combination of a heel-seat die for shaping the heel-seat portion only of a shoe for the reception of a wood heel, a shoe support constructed and arranged to have sufficient relative positioning movement in a plane substantially normal to the direction of heel-seat forming pressure to enable the shoe to be properly located with respect to the die, manually operated means for effecting preliminary movements of the support toward and from the die to enable the operator to press and hold the shoe against the die and to release the shoe and reposition it with respect to the die when it is not properly positioned, and means for effecting further move-

ment of the shoe support to effect molding of the heel-seat by the die.

16. In a heel-seat forming machine, the combination of a heel-seat forming die having its face tilted at a substantial angle to the horizontal, a last support movable in a direction perpendicular to the face of the die, and power means for relatively moving the die and support to form the heel-seat.

17. In a heel-seat forming machine, the combination of a sliding shaft tilted rearwardly approximately ten degrees from the vertical, a shoe support on said shaft, a heel-seat die with its face perpendicular to the direction of movement of the sliding shaft and aligned therewith, and power means for operating the shaft to force the heel-seat of a shoe on the support against the die.

18. In a machine for forming the heel-seats of boots and shoes, the combination of a heel-seat forming die, a last support, and means for applying heavy pressure to the heel-seat of the shoe, the die and last support being arranged so that the longitudinal axis of the shoe extends at an angle of substantially forty-five degrees to the fore-and-aft plane of the machine to facilitate pounding the counter portion of the shoe while the heel-seat is under pressure.

19. In a machine for forming the heel-seats of shoes for the reception of wood heels, the combination of a heel-seat die, and a shoe support constructed and arranged so that the shoe will be held with its longitudinal axis extending away from the operator and toward his left to render the counter portion readily accessible for the pounding operation, with means for effecting relative movement between the die and shoe support to form the heel-seat and hold it under pressure.

20. In a heel-seat forming machine, the combination of a heel-seat die, a shoe support, and means for relatively moving the die and the support perpendicularly to the face of the die to force the die upon the heel-seat material, the pressure being directed backwardly away from the operator substantially ten degrees from the vertical to afford the operator a better view of the die and heel-seat.

21. In a machine for forming the heel-seats of boots and shoes, the combination of a heel-seat die, a shoe support, a toggle for raising the shoe support, an eccentric connected to said toggle and having a projection, and a pawl arranged to engage the projection on the eccentric for preventing backward movement of the eccentric when the machine stops with the weight of the eccentric horizontally offset with respect to its axis.

22. In a machine for forming the heel-seats of boots and shoes, the combination of a heel-seat die, a shoe support, means for relatively moving the die and support to apply pressure to the shoe, a powerful spring

- for determining the pressure so applied, a clutch for driving said means, power means for driving the clutch, and means acting when the machine is restarted with the spring under tension to prevent reaction of the spring from moving the clutch driven means faster than the power means.
23. In a machine for forming the heel-seats of boots and shoes, the combination of a heel-seat forming die, a shoe support, a heavy spring, means for effecting relative movement of the die and shoe support and for tensioning said spring, a clutch for operating said means, and means for preventing the driven member of the clutch from racing ahead of the driving member when the clutch is thrown in to release the pressure and the spring reacts.
24. In a machine for forming the heel-seats of boots and shoes, the combination of a heel-seat die, a shoe support movable toward the die, a spring, means for forcing the shoe support toward the die by compression of the spring, a clutch for operating said means arranged to stop the machine with the work under pressure of the spring, a brake, and means acting when the machine is restarted for applying the brake to prevent the spring from reacting too suddenly.
25. In a machine for forming the heel-seats of boots and shoes, the combination of a heel-seat die, a shoe support movable toward the die, a spring, power means for forcing the support toward the die by compression of the spring, mechanism for controlling said power means and for stopping the machine with the spring under tension, said mechanism comprising a driven member and a driving member, a drum on the driven member, a band embracing the drum, and means for tightening the band on the drum when the machine is restarted with the spring under tension.
26. In a machine for forming the heel-seats of boots and shoes, the combination of a heel-seat die, a shoe support movable toward the die, a spring, power means for forcing the support toward the die by compression of the spring, a clutch for controlling said power means comprising a driven member and a driving member, a drum on the driven member, a band embracing the drum, a pivoted arm to which the ends of the band are attached, the arm also bearing on the drum, and a cam acting to pull on one end of the band to tension it during that part of the cycle when the spring is reacting.
27. In a heel-seat forming machine, the combination of a heel-seat forming die, a shoe support constructed and arranged to present a shoe bottom up to the die and for movement heightwise of the shoe toward the die, said shoe support being constructed and arranged for positioning movements in directions which are substantially normal to the direction of movement of the shoe support toward the die, means for moving the shoe support toward the die to bring the shoe and die into contact and to apply sufficient pressure to hold the shoe and die in proper position relatively to each other, and means for further moving the shoe support toward the die to impart the shape of the die to the heel-seat material.
28. In a heel-seat forming machine, the combination of a heel-seat forming die, a shoe support constructed and arranged to present a shoe bottom up to the die and to move heightwise of the shoe toward the die, said shoe support being constructed and arranged for positioning movements in directions which are substantially normal to the direction of movement of the shoe support toward the die and also constructed and arranged for tipping movement laterally of the shoe, means for moving the shoe support toward the die for bringing the shoe and die into contact to permit the operator by inspection of the shoe and die to determine the proper position of the shoe with respect to the die and for applying sufficient pressure to hold the shoe and die in proper position relatively to one another, and means for further moving the support toward the die to impart the shape of the die to the heel-seat material.
29. In a machine for forming the heel-seats of boots and shoes, the combination of a heel-seat die, a shoe support, means including driving and driven members for moving the support to press a shoe, a powerful spring for determining the pressure applied to the shoe, an eccentric on the driven member, a toggle operated by the eccentric between the spring and the shoe support, a clutch between the driving and driven members, and means acting when the machine is restarted with the spring under tension for preventing forward movement of the eccentric relatively to the driving member.

In testimony whereof I have signed my name to this specification.

RENÉ E. DUPLESSIS.
